CLAIM

The ornamental design for a wristband, as shown and described.

DESCRIPTION

FIG. 1 is a perspective view of the wristband showing my new design;

FIG. 2 is an enlarged fragmented view of the hemming portion thereof; and,

FIG. 3 is a top plan view thereof, the bottom is a mirror image.

The broken line showing of the human form in FIG. 1 is for illustrative purposes only and forms no part of the claimed design.

1 Claim, 1 Drawing Sheet

FIG. 2

FIG. 1

FIG. 3
